UNITED STATES PATENT OFFICE.

DAVID R. JONES, JR., OF DUBUQUE, IOWA, ASSIGNOR TO JONES BROS. OVERALL CO., OF DUBUQUE, IOWA, A CORPORATION OF IOWA.

CHILD'S UNDERGARMENT.

1,249,108.

Specification of Letters Patent.

Patented Dec. 4, 1917.

Application filed May 27, 1916. Serial No. 100,279.

To all whom it may concern:

Be it known that I, DAVID R. JONES, Jr., a citizen of the United States, residing at Dubuque, in the county of Dubuque and 5 State of Iowa, have invented certain new and useful Improvements in Children's Undergarments, of which the following is a specification.

This invention relates in general to under-
10 wear and has more particular reference to an undergarment for children. In clothing children, and particularly little girls, a waist is frequently worn in addition to the under-clothing, the waist being equipped with but-
15 tons to which the child's drawers and garters are attached and by which they are sup-
20 ported. My invention, however, contem-
pates the provision of a garment in the
form of a union suit to which both the
drawers and the garters may be attached,
thus eliminating the necessity of wearing a
25 waist which in summertime is warm and un-
comfortable.

My invention also contemplates the pro-
25 vision of a garment of this character which
will eliminate the necessity of unbuttoning
two sets of buttons in order to let down the
seat of the drawers and of the undergar-
ment, which, in the present instance, is in
30 the form of a union suit.

Another object of my invention is to so
locate the garter-supporting tabs that the
pull exerted by them will be transmitted to
35 both the front and rear shoulder straps of
the garment thereby imposing a direct and
comfortable pull upon the shoulders instead
of a pull which has a tendency to lower the
front and elevate the rear of the garment to
40 the discomfort of the wearer.

Still another object is the provision of an
undergarment having shoulder straps which
are capable of adjustment so that they may
be lengthened or shortened to accommodate
the garment to wearers of different sizes.
45 For the purpose of facilitating an under-
standing of my invention I have illustrated
one preferred embodiment thereof on the
accompanying drawings, from an inspection
50 of which when considered in connection
with the following description the invention
and many of its attendant advantages
should be readily understood. Referring to
the drawings—

Figure 1 is a front view of a garment em-
55 bodying my invention, and

Fig. 2 is a rear view thereof.

By reference to the drawings it will be observed that the garment illustrated comprises a body portion 3, preferably cut to button up the front, and formed beneath the 60 waist-line to provide the legs 4 of a pair of underdrawers, the garment as a whole being in the form of a union suit. The upper portion of the garment is shaped to provide a neck-opening 5 and armholes 6, and is sup- 65 ported upon the wearer by front and rear shoulder straps 7 and 8 respectively, each front strap and its companion rear strap being adjustably connected over the wearer's shoulders so that the straps may be lengthened or shortened to accommodate the garment to wearers of different sizes. The structure employed for effecting this adjustment consists of a pair of buttons 9 attached to each front strap and a plurality of pairs 70 of correspondingly positioned button holes 11 formed in each rear shoulder strap. It will be obvious that by buttoning the buttons 9 into the button holes 11 more or less remote from the ends of the rear shoulder 75 straps the effective length of the straps may be varied to meet the comfort of the wearer.

In order that the drawers or pants which children customarily wear over such a union suit may be supported without encumbering 80 the child with an unnecessary garment in the form of a waist I have equipped the garment with a series of drawer-supporting buttons 12 which are arranged around the waist-line of the garment. It will be observed 85 from Fig. 2 that the garment disclosed is of the drop seat variety, the upper or free edge 13 of the seat being provided with button holes 14 adapted to be engaged with buttons 15 arranged upon the back of the garment, a reinforcing strip or band 16 being 90 preferably employed to provide a firm and secure anchorage for the buttons.

If the drawer-supporting buttons 12 were attached to the garment at or above the 100 waist-line it will be obvious that in order to lower the seat of the drawers it would be necessary to unbutton the drawers from these buttons 12, and in order to lower the drop seat of the union suit it would also be 105 necessary to unbutton the buttons 15. My invention, however, provides a very handy garment by locating the drawer-supporting buttons 12 at or near the upper or free edge of the drop seat of the garment so that the 110 seat of the drawers is supported from and is raised and lowered with the drop seat of the

garment. It will thus be obvious that the seat of the drawers and the drop seat of the garment may be lowered simultaneously by simply unbuttoning the buttons 15.

5 Another feature of my invention resides in the location of the garter-supporting tabs or loops 17 to which the upper ends of the child's garters are attached. In garments now on the market these tabs are located at 10 the front of the garment substantially in the position that the front drawer-supporting buttons 12 are shown in Fig. 1. When located in this position the hold of the garters on the tabs pulls downwardly on the front 15 shoulder straps which in turn pull upwardly on the rear shoulder straps, thereby causing the garment to be pulled down in front and up in the rear. Such an arrangement and its results are manifestly uncomfortable to 20 the wearer. I have, with a view to overcoming the objectionable feature mentioned, located the garter-supporting tabs 17 directly beneath the arm-holes and in close proximity to the side seams of the garment, so 25 that the pull exerted by the tabs is transmitted to both the front and rear shoulder straps and the weight is therefore carried evenly by the front and rear straps with the result that there is no tendency for the garment 30 to pull down in front and up in the rear. This arrangement of the garter tabs

contributes materially to the comfortable-
ness of the garment.

It is believed that my invention and many of its inherent advantages will be understood from the foregoing without further description but it should be obvious that the size, shape and proportion of various elements of the garment are capable of considerable modification and variation without departing from the essence of the invention as defined by the following claims.

I claim:

1. A child's undergarment, comprising a union suit having a drop seat adapted to be 45 detachably fastened along its free edges to the body of the garment, and drawer-supporting means secured to said drop seat adjacent to said free edge thereof whereby by the seat of a pair of drawers attached to 50 said supporting means is raised and lowered by and with said drop seat.

2. A child's undergarment, comprising a union suit having a drop seat detachably fastened at its free edge to the body of the 55 garment along the waist-line thereof, and drawer-supporting means carried by said garment below said waist-line, said means at the back of the garment being attached to and carried by said drop seat.

DAVID R. JONES, JR.
